TERMINAL LINK FOR A BRACELET OR THE LIKE

Jeanne Allen Sharp and Sherie Kent Spitz,
Brooklyn, N. Y.

Application February 9, 1955, Serial No. 34,425

Term of patent 7 years

(Cl. D45—4)

FIG.1

We claim:

The ornamental design for a terminal link for a bracelet or the like, substantially as shown.
